ELECTRICAL CONTROL SYSTEM

Keith E. Barwick, Detroit, Mich., assignor to
Weltronic Company, Detroit, Mich., a corporation of Michigan

Application October 18, 1946, Serial No. 703,982

12 Claims. (Cl. 315—268)

1
This invention relates to electrical control systems and is particularly directed toward an improved and simplified means for controlling automatic welding equipment of the impulse type.

The principal objects of this invention are to provide a simple, reliable, and efficient control of the aforesaid type; to provide such a control which, when once energized, will maintain itself energized until the completion of a full welding cycle irrespective of the condition of the initiating switch; to provide in such control a transformer having a plurality of primary windings arranged in bucking relation; and to generally simplify controls of the type described.

With the above, as well as other more detailed objects in view which appear from the following description and the appended claims, there is shown in the drawing a preferred but illustrative embodiment of the invention.

In the drawing which is to be taken as a part of this specification there is illustrated diagrammatically a control system embodying the invention.

The control system comprises an initiating network 2, a sequence network 4, a timing network 6, a firing network 8, and a power network 10 so constructed and arranged that the initiating network 2 initiates operation of the sequence network 4 which controls the timing network 6 which in turn energizes the firing network 8 for rendering the power network 10 conductive.

The initiating network 2 comprises a pair of discontinuous-type grid-controlled leading and trailing electronic valves V1 and V2 and a pair of bias controlling transformers T1 and T2. The anode of valve V1 is directly connected to the cathode of valve V2; to the center tap connection of the secondary winding of transformer T2, and to the line L1 by a conductor 12. A conductor 14 connects the center tap of the secondary winding of the transformer T1 to the cathode of the valve V1, to the anode of the valve V2, and to one terminal 16 of the actuating coil of a solenoid valve SV, the other terminal of the valve SV being connected to the line L2. The grid of the valve V1 is connected through a parallelly arranged resistance and capacitor to the upper terminal of the secondary winding of the transformer T1, and the intermediate terminal of this winding is connected to the cathode of the valve V1 whereby the upper half 17 of this winding is operable to bias the grid of the valve V1 with respect to its cathode. The lower half of this same winding of the transformer T1 is used as a primary winding and will be hereinafter referred to

as primary winding 18. A resistor R1 is connected across the terminals of the primary winding 18 and has an intermediate tap connection which is connected by means of conductors 21 and 22 to the line L2. A condenser C1 is arranged in parallel with the lower portion of the resistor R1, and a condenser C2 is connected between the lower terminal of the primary winding 18 and the upper terminal of the secondary winding 17.

2
The primary winding of the transformer T1 has a center tap connection dividing it into primary winding 24 and primary winding 26. A conductor 27 having in series therewith a parallelly arranged resistor R3 and condenser C3 connects the center tap or common terminal of the windings 24 and 26 to the conductor 22 connected to line L2. The upper terminal of the winding 26 is connected through the contact *a* of a time-delay switch TD and through the normally open contacts of a manually operated initiating switch SW1 to the line L1 while the lower terminal of the winding 24 is directly connected by means of conductor 28 to the line L1. The transformer T2 is arranged to provide a control bias for the valve V2 and has the upper terminal of its secondary winding connected through a parallelly arranged resistor and capacitor to the grid thereof and its center tap connection directly connected to the cathode thereof. A capacitor C4 is connected between the terminals of the secondary winding of the transformer T2 for phase control. The upper half of the primary winding of the transformer T2 is in parallel circuit relation with the valve SV, its upper terminal being directly connected to terminal 16 and its center tap being connected through a resistor R4 to the line L2. The lower half of this primary winding is connected between the lines L1 and L2 in series with the resistor R4.

The sequence network 4 comprises a plurality of discontinuous-type grid-controlled valves V3—V8, each having its anode directly connected to one terminal of separate secondary windings 45 of a transformer T3, the primary winding of which is connected between the lines L1 and L2. The terminals of the secondary windings of the transformer T3 opposite those connected to the anodes of the valves V3—V8 are connected through impedance networks comprising parallelly arranged capacitors and resistors to a common cathode bus 32. The impedance network associated with the valves V3, V5, V7, and V8 comprises time-delay networks or means TD3, TD5, TD7, and TD8, each having a parallelly arranged

condenser C5 and variable resistor R5, while the impedance networks associated with the valves V4 and V6 each comprise a condenser C6 and a resistor R6 arranged in parallel circuit and having their values so related with respect to each other that each condenser C6 is operable to discharge through its resistor R6 in the time required for the lines L1 and L2 to go through two or three complete voltage cycles.

The conductivity of each of the valves V4—V8 is controlled by the valves V3—V7 respectively, since the grids of these valves V4—V8 are each connected through resistors to the terminal of the impedance network of the valves V3—V7 respectively opposite to that which is connected to the common bus 32, so that, for example, if valve V3 is conducting, the grid of valve V4 will be negative with respect to the bus 32. The conductivity of the valve V3 is controlled by a transformer T4 having a secondary winding, one terminal of which is connected through a parallelly arranged resistor and capacitor to the grid of valve V3 and the other terminal of which is directly connected to the bus 32. The primary winding of the transformer T4 is divided into two parts by an intermediate connection providing primary windings 33 and 34. The winding 34 is connected in shunt with the solenoid valve SV by the conductors 35 and 36 connected respectively to the conductors 14 and 27. Conductor 35 is also connected to bus 32 whereby the potential thereof is held at the potential of the terminal 16 of the valve SV. The winding 33 is connected between the lines L1 and L2 in series with the switches SW1 and TD and a "single operation-repeat operation" switch SW2. As will be more fully described hereinafter, the valve V3 is normally maintained conductive due to the normally de-energized condition of the winding 34 and valve SV, but is rendered in a nonconducting or blocked condition when either or both of the windings 33 and 34 are energized.

The timing network 6 comprises a valve V9 controlled by the network 4 and a pair of back-to-back arranged leading and trailing valves V10 and V11. The valve V9 has two controlling grids, either one of which, when biased negatively, will prevent the valve from becoming conductive. The cathode of the valve V9 is maintained at the same potential as the bus 32 by a conductor 37 which connects the bus 32 to the cathode of valve V9. One of the controlling grids is connected through a parallelly arranged resistor R7 and capacitor C7 to the grid of the valve V4, while its other grid is connected through a resistance R8 to the grid of the valve V1 so that valve V9 is operable to conduct only during that time that both the valves V4 and V1 are conductive. The anode potential for the valve V9 is supplied by a transformer T5, the primary winding of which is connected in parallel with the solenoid valve SV by means of a conductor 38, having a manually operated "weld-no weld" switch SW3 and a pressure-actuated switch SW4, connected from one terminal of the primary winding to the line L2 and by a conductor 40 which connects the other terminal of the primary winding to the bus 32. It will be noted that the bus 32 is connected by conductor 35 to the conductor 14 which is in turn connected to the terminal 16 of the actuating coil of the solenoid valve SV.

One terminal of the secondary winding of the transformer T5 is directly connected to the anode of the valve V9, while the other terminal is connected by conductor 42 to the cathode of the

valve V10. The grid of this valve is connected by a conductor 44, having in series therewith a parallelly connected resistor R10 and capacitor C10, to the cathode of the valve V9. A capacitor C11 is connected between the cathode of valve V9 and conductor 42. One terminal of the secondary winding of a transformer T6 is connected to conductor 42 and the other terminal of this secondary winding is connected through a parallelly arranged resistor R9 and capacitor C9 to the grid of the leading valve V10. A resistor R12 is connected between the grid and cathode of valve V10 to insure that the valve V10 conducts immediately after the valve V9 conducts and the anode of valve V10 is positive. The primary winding of the transformer T6 is connected between the lines L1 and L2 by conductors 46 and 48 so that it is continually energized as long as the line switches LS1 and LS2 are closed and is polarized so that its output voltage will be effective to render the grid of the valve V10 negative whenever the potential of the anode of the valve V10 is positive with respect to its cathode. However, when the valve V9 is conducting, the potential of transformer T5 opposes that of the transformer T6 so that the grid of the valve V10 will be properly biased to permit the valve V10 to conduct.

The anode of the valve V10 and the cathode of the valve V11 are connected together and to the line L3 by a conductor 50, while the cathode of the valve V10 and anode of the valve V11 are connected together and to line L4 by a conductor 52 having in series therewith the primary winding of a kick transformer T7. The primary winding of a transformer T8 is continually connected between the lines L3 and L4, one terminal being connected to the conductor 50 by a conductor 54 and the other terminal being connected to the portion of the conductor 52 between the transformer T7 and line L4. One terminal of each of the secondary windings of the transformers T7 and T8 are connected together by a conductor 55. The other terminal of the secondary winding of transformer T7 is connected through a parallelly arranged resistor and capacitor to the grid of valve V11, while the other terminal of the secondary winding of the transformer T8 is connected through the conductor 54 to the cathode of valve V11. The voltage of the transformer T8 is such that it is effective, when acting alone, to render the grid of the valve V11 negative with respect to its cathode whenever the anode of valve V11 is positive with respect to its cathode. The kick transformer T7 is arranged so that whenever the valve V10 is conductive during a half cycle of current, the collapse of flux therein holds the grid of the valve V11 in condition to permit the valve V11 to conduct during the subsequent half cycle. The valve V11 therefore will not conduct unless the valve V10 has conducted during the preceding half cycle and will always conduct during a subsequent half cycle to a half cycle that valve V10 conducts.

The firing network 8 comprises a transformer T9, a saturable reactor 56, and a current-limiting reactor 58. One terminal of the primary winding of the transformer T9 is connected by a conductor 60 to the conductor 42, while the other terminal is connected through the saturable reactor 56 and current-limiting reactor 58 to one terminal 62 of a welding transformer WT having its other terminal directly connected to the line L4. A switch SW4 is arranged to shunt out the reactor 58 when lines L3 and L4 are supplied

with 220-volt power and to be opened when 440-volt power is being supplied. When the valves V10 and V11 are conducting, current will flow between the lines L3 and L4 through the conductor 50, valve V10 or V11, conductors 52 and 60, reactors 56 and 58, and the welding transformer WT to energize the transformer T9. A pair of secondary windings of transformer T9 are connected respectively through rectifiers 64 and 66 to the igniters and cathodes of mercury pool-type power-controlling valves V12 and V13 respectively. It will be noted that when the valves V10 and V11 conduct, the transformer T9 and reactors 56 and 58 are in parallel circuit with the valves V12 and V13, and the potential thereacross is the potential between the cathodes and anodes of the power-controlling valves. Therefore, when the valves V12 or V13 fire, the igniters are practically de-energized, and no deteriorating voltage is maintained on the igniter of the valves V12 and V13. Reactor 56 is adjustable in its time of saturation to provide for firing the valves V12 and V13 at adjustable points along the voltage wave between the lines L3 and L4 to provide for controlling the welding heat as is more fully described and claimed in the co-pending application of Clément J. Collom, Serial No. 681,758, filed July 6, 1946; and assigned to the same assignee as is the present invention.

It is thought that the remaining details of the system may best be understood with reference to a description of the operation thereof. Assuming that it is desired to condition the system for repeat operation, the switch SW2 is open-circuited and the usual disconnect line switches LS1 and LS2 are closed, thereby connecting the line conductors L1 and L2 to the source of supply which may be a conventional 60-cycle alternating current 110-volt system. The disconnect line switches LS3 and LS4, which may be mechanically connected to the switches LS1 and LS2, are also closed, thereby connecting the line conductors L3 and L4 to a suitable source of supply which may be a conventional 60-cycle alternating current 220- or 440-volt system, switch SW4 being set accordingly as hereinbefore described. Energization of the lines L1 and L2 energizes primary winding 24 of the transformer T1 and the lower half of the primary winding of the transformer T2 whereby a biasing voltage is applied between the grid and cathode of the valves V1 and V2 respectively to maintain the valves in a blocked condition. Closure of the line switches LS1 and LS2 also energizes the transformer T3 having a secondary winding, the terminals of which, as indicated by the letters *xx* appearing on the winding and on the cathode heaters, are connected to energize the cathode heaters of the valves V1-V11 inclusive. The transformers T6 and T8 were also energized upon closure of the line switches LS1 and LS2 to provide respectively a blocking bias voltage between the grid and cathode of the valves V10 and V11. Closure of the line switches LS3 and LS4 prepared the firing network 8 and the power network 10 for operation by the network 4. Energization of the transformer T3 also energized the time-delay means TD which is operable after a predetermined time delay to close its contacts *a*, whereby the initiating network 2 may be operated by the closure of the switch SW1. As soon as the valves V3-V8 inclusive are all rendered in an operative condition due to heating of their cathodes by their respective cathode heaters, the valves V3, V5, and V7 will become conductive

and the valves V4, V6, and V8 will become non-conductive or blocked. Since under this condition the switch SW2 is open and valves V1 and V2 are nonconductive, there will be no potential placed across the primary windings 33 and 34, and therefore the grid of the valve V3 will be at the same potential as the cathode thereof due to its interconnection through the secondary winding of the transformer T4 which is connected between the grid and common cathode bus 32. Conduction of the valve V3 causes a potential drop to appear across the time-delay means TD3 which maintains the grid of the valve V4 negative with respect to the bus 32 and the valve V4 blocked. Since no current is flowing in the anode circuit of the valve V4, there will be no drop across the impedance network thereof comprising the resistor R6 and capacitor C6 so that the grid of the valve V5 will be at the same potential as the cathode thereof and this valve will be conductive. Conduction of the valve V5 causes a potential drop to appear across the time-delay network TD5 which will maintain the grid of the valve V6 negative with respect to the cathode thereof, and the valve V6 will therefore be in a blocked condition. Since no current is flowing through the impedance network of the valve V6, the grid of the valve V7 will be maintained at the same potential as the cathode thereof, and the valve V7 will be in a conducting condition, causing current to flow through its time-delay network TD7, thereby maintaining the grid of the valve V8 negative with respect to the cathode thereof, and the valve V8 will be held blocked. The right-hand grid of the valve V9 which is connected to the grid of the valve V7 will be maintained at the same potential with respect to its cathode as the grid of the valve V7 with respect to its cathode.

Since the valve V8 is not conducting, the conductor 66 which is electrically connected to the terminal of the impedance network of the valve V8 opposite to that connected to the bus 32 and to the grid of the valve V1 is conducting current from the upper terminal of the winding 17 through the impedance network TD8, the common bus 32 and conductor 35 back to the lower terminal of the winding 17. This conduction is without any operational effect upon the system, since the potential supplied by the winding 17 is quite sufficient to maintain the grid in a condition to block the valve V1 in spite of the added potential drop through the resistor in the grid circuit of the valve V1.

Before a stabilized condition of the valves V3-V8 is reached, certain of these valves may fire out of order because of the fact that they have not as yet had the proper biases placed between their grids and cathodes. Such operation is without effect, however, due to the open condition of the switch SW4 which is controlled by the outlet fluid pressure of the solenoid valve SV. The switch SW4 is closed only when the valve SV is in open position and a predetermined fluid pressure is being supplied to hold the welding electrodes E against the work W. The solenoid valve SV has not as yet been energized because of the bias being continually placed between the grid and cathode of the valves V1 and V2 by the transformers T1 and T2. The valves V12 and V13 can only fire subsequent to the firing of the valves V10 and V11, and these valves are likewise continually maintained in a blocked condition until such time as the valves V10 and V11 fire.

After a predetermined time delay which is

sufficiently ample to permit all of the valves V3—V8 to come to their stabilized condition, the networks 2, 4, 6, 8, and 10 are ready for operation. Before a welding cycle can be initiated, the switch SW3 must first be closed. The switch SW1 is then closed, energizing the primary winding 26 of the transformer T1, which energization acts to buck the flux in the core thereof due to the primary winding 24. This removes the blocking bias between the grid and cathode of the valve V1 and the valve V1 conducts. Conduction of the valve V1 causes current to flow from the line L1 through the conductor 12, the valve V1, conductor 14, and the energizing coil of the solenoid valve SV to the line L2. At the same time, current also flows from the line L1 through the upper half of the primary winding of the transformer T2 and the resistor R4 to the line L2, through the winding 18 of transformer T1, the lower portion of the resistor R1, and capacitor C1, and through the primary winding 34 of transformer T4, which circuits are in shunt relation to the valve SV.

Current through the winding 18 aids the current flow through the winding 26 in its bucking effect of the flux produced in the core of the transformer T1 by the current flow through the winding 24. If the switch SW1 at this time is still in closed position, this is without substantive effect on the operation of the network 2 other than to place on valve V1 a bias somewhat more favorable to its already conductive condition. Current flow through the winding 34 of transformer T4 places a blocking potential between the grid and cathode of the valve V3 and renders the same nonconductive at the end of its conducting half cycle. Current flow through this upper half of the primary winding of transformer T2 tends to buck the flux due to current flow through the lower half of this primary winding so that, at the next half cycle of the voltage wave between the lines L1 and L2 when the anode of the valve V2 becomes positive with respect to the cathode thereof, the grid of the valve V2 will not be immediately rendered negative with respect to the cathode thereof due to the phasing effect of the capacitor C4 and the impedance of the primary winding of the transformer T2 so that the valve V2 will become conductive. Conduction of the valve V2 again establishes the circuit through the energizing winding of the solenoid valve SV and the windings 18 and 34 and upper half of the primary winding of transformer T2 as above identified, except that it flows in the opposite direction and through valve V2 instead of through valve V1. As the flux collapses in the core of the transformer T1 at the end of the half cycle in which the line L2 is positive with respect to the line L1, the condenser C2, which was charged during this time, discharges through the windings 17 and 18 arranged in series connection which opposes the build up in flux in the core of the transformer T1 due to energization of the primary winding 24, so that the grid of the valve V1 is not rendered negative with respect to the cathode thereof and the valve V1 is rendered conductive. This subsequent conduction of the valve V1 after initial conduction due to closure of the switch SW1 will continue in the above-identified manner irrespective of the open or closed circuit condition of the switch SW1 and will be terminated only upon completion of the full cycle of operation of the sequence network 4 in a manner to be herein-after described.

After the circuit through the energizing coil of the solenoid valve SV was energized, the primary

winding 34 of the transformer T4 was also energized as hereinbefore described. This caused a voltage to be induced in its secondary winding which biases the grid of the valve V3 negative with respect to its cathode to render the valve V3 non-conductive. This rendering of the valve V3 non-conductive is without immediate effect due to the potential maintaining feature of the time-delay means TD3. Subsequent to a predetermined time interval after blocking of the valve V3, the capacitor C5 of the time-delay means TD3 will have discharged through its associated resistor R5 to render the grid of the valve V4 at the same potential as the bus 32. This time interval between the time that the solenoid valve SV was energized and the time that the time-delay means TD3 is timed out so that the grid of the valve V4 is rendered at the same potential as the bus 32 is the clamping or squeeze time of the welding apparatus and represents the time interval between the time that the welding electrodes E were brought against the work W and the time that the valve V9 is rendered conductive to initiate flow of welding through the welding transformer WT. As the time-delay means TD3 times out, the left-hand grid of the valve V9 will no longer be maintained negative with respect to the cathode thereof, and since the right-hand grid of the valve V9 at this time is at cathode potential, the valve V9 will conduct and oppose the potential of the transformer T6 to render the valve V10 conductive. As the valve V10 becomes conductive, current will flow from the line L3 through the conductor 50 through the valve V10 and conductors 42 and 60 to the primary winding of the transformer T9. From the primary winding of the transformer T9, the current flows through the saturable reactor 56, the current limiting reactor 58, and the primary winding of the welding transformer to the line L4. At a predetermined time interval, which is always a fraction of a half cycle of the voltage wave between the lines L3 and L4, the saturable reactor 56 will saturate, permitting the critical voltage to be supplied by the left-hand secondary coil of the transformer T9 between the igniter and cathode of the valve V12 to render the valve V12 conductive. Conduction of the valve V12 causes current to flow from the line L3 through the valve V12 and the welding transformer WT to the line L4. Conduction of the valve V10 also causes current to flow through the primary winding of the transformer T7 to the line L2, so that at the end of this half cycle during which the line L1 was positive with respect to the line L2, the collapse of flux in the kick transformer T7 will induce a potential in the secondary winding thereof which overcomes the potential induced in the secondary winding of the transformer T8 so that the grid of the valve V11 is not rendered negative with respect to its cathode before the valve V11 conducts. Once conducting, the valve V11 will permit current to flow from the line L4 through the primary winding of the welding transformer WT, the reactors 56 and 58, the transformer T9, the conductor 60, the valve V11 and conductor 50 to the line L3. The flow of current through this just-mentioned circuit, depending upon the time taken to saturate the saturable reactor 56, will cause the critical potential to be applied between the igniter and cathode of the valve V13 for rendering it conductive to permit current flow from the line L4 through the welding transformer WT, the valve V13 back to the line L3.

At the time the time-delay means TD3 timed out the valve V4 was also rendered conductive, causing a potential to be established across its anode impedance circuit, thereby rendering the grid of the valve V5 negative with respect to its cathode to block the valve V5. The rendering of valve V5 nonconductive is without immediate effect due to the time-delay network TD5 which maintains the grid of the valve V6 negative and consequently the valve V6 blocked for a predetermined time interval subsequent to blocking of the valve V5. This time interval is the welding time, since at the expiration of this time interval the grid of the valve V6 will be rendered at cathode potential and valve V6 will become conductive. Upon conduction of valve V6 a potential will be established across the impedance network of its anode circuit, rendering the grids of the valves V7 and V9 negative with respect to their cathodes and consequently the valves nonconductive. The means TD5 therefore controls the welding time or interval when valve V9 is conductive.

Rendering of the valve V7 blocked is without immediate effect, but as soon as the time-delay means TD7 times out, the valve V8 will be rendered conductive because its grid will then be at cathode potential. The time interval represented by the time of the means TD7 is the "hold time" or time that the electrodes E are held against the work W during cooling of the weld. Conduction of the valve V8 establishes a potential across its time-delay means TD8 which renders the potential of the conductor 66 negative with respect to the bus 32 and with respect to the cathode of valve V1 which is connected thereto by the conductors 14 and 35. The negative potential of the conductor 66 is of sufficient magnitude to hold the grid of the valve V1 negative with respect to its associated cathode and hold the valve V1 against subsequent firing, thereby de-energizing the solenoid valve SV and permitting the electrodes E to be released from the work W. The valve V2 will not again be rendered conductive, since the upper half of the primary winding of transformer T2 was likewise de-energized, permitting the lower half of this winding to bias the valve V2 nonconductive.

Winding 34 which is also in parallel circuit with the valve SV is also de-energized to initiate the resetting cycle of operation of the sequence network 4 by removing the blocking bias on valve V3 so that it is rendered conductive. Conduction of valve V3 re-establishes the potential drop across its anode impedance network rendering the valve V4 blocked which removes the blocking bias on the grid of valve V5. Valve V5 then becomes conductive, establishing, due to the potential drop across its time-delay means TD5, a blocking bias on the grid of valve V6, rendering this valve nonconductive. With valve V6 nonconductive, the grid of valve V7 goes to cathode potential, and valve V7 becomes conductive, re-establishing a potential drop across its time-delay means TD7, rendering the grid of valve V8 negative with respect to its cathode, and valve V8 nonconductive. Rendering of valve V8 blocked is without immediate effect, due to the action of the time-delay means TD8 which will maintain a potential thereacross for a predetermined time interval subsequent to the blocking of the valve V8. This interval is the "off time" period of the welding machine or time when the electrodes E are maintained parted.

As the time-delay means TD8 times out, the

negative potential impressed thereby on the grid of the valve V1 disappears, and, assuming the switch SW1 to be closed, indicating that the desired welding has not been completed, the valve V1 will again be rendered conductive in the same manner as is described hereinbefore, and the welding cycle will be repeated. If, however, the switch SW1 has been opened, the networks will remain in this stable condition until the switch SW1 is again closed, because the only primary or input winding of the transformer T1 which is energized is winding 24, and the effect of this winding is to maintain valve V1 blocked.

If now the switch SW2 had been in closed circuit or single-weld position, the cycle of operation just described in connection with the "repeat weld" or open-circuit condition of switch SW2 would be interrupted at the time valve V8 was rendered conductive and before the resetting cycle of network 4 was initiated. This interruption is due to the energization of the winding 33 of transformer T4, which is polarized so that current flow therethrough aids the current flow through the winding 34 in placing a blocking bias potential on the grid of the valve V3. The valve V3, therefore, will remain in a blocked or nonconductive condition, even though the winding 34 is de-energized due to the nonconductive condition of the valves V1 and V2. Since the valve V3 is maintained blocked, the network 4 cannot go through its resetting cycle of operation and will remain in that condition as long as the switch SW1 remains closed. Opening of the switch SW1 de-energizes the winding 33, permitting valve V3 to become conductive and the resetting cycle of network 4 to occur in the manner described in connection with the repeat operation. If, however, the switch SW1 is opened prior to the completion of the initial portion of the operation of the sequence network 4, the welding cycle will continue through its resetting cycle just as if the switch SW2 were in repeat or open position, but, as set forth with respect to the repeat operation, another welding cycle will not be initiated, because at this time only the winding 24 of transformer T1 is energized, and this winding acts to hold the valve V1 blocked.

The switch SW3 is normally maintained in closed circuit position but may be opened in the event it is desired to go through all of the welding steps without welding current actually flowing. Switch SW4 prevents welding current from flowing in the event the fluid pressure to the electrodes fails for any reason.

Although only a single specific embodiment of the invention has been disclosed in detail, it will be appreciated that various modifications in the form, number, and arrangement of parts may be made without departing from the spirit and scope of the invention.

What is claimed and is desired to be secured by United States Letters Patent is as follows:

1. In an electrical controlling network, electronic valve means having a cathode and a controlling grid, potential supplying means electrically connected between said cathode and said grid for applying a bias potential to control the conduction of said valve means, means for controlling the magnitude of said potential applied between said cathode and said grid and operable upon energization to render said supplying means ineffective to supply said bias potential, and a second controlling means energized independently of said first controlling means for rendering

11

said supplying means ineffective to supply said potential.

2. In an electrical controlling network, a pair of electronic valves connected back to back, one of said valves having a cathode and a controlling grid, potential supplying means electrically connected between said grid and said cathode for biasing said grid with respect to said cathode for maintaining said one valve nonconductive, means rendering said biasing means ineffective to supply said potential, and means energizable as a consequence of an operating condition of the other of said valves for rendering said biasing means ineffective to supply said potential.

3. In an electrical controlling network, a transformer having a single core and a plurality of windings, each said winding having a pair of terminals, an electronic valve having a cathode and a controlling grid, circuit means connecting the terminals of one of said windings between said grid and said cathode, circuit means connecting the terminals of another of said windings across a source of electrical supply potential, and means electrically connecting the terminals of a third of said windings to said supply potential in opposite polarity relative to the connection of said other winding whereby current flow through said third winding opposes the build up of flux in said core due to flow of current through said second winding thereby to vary the voltage output of said first winding.

4. In an electrical controlling network, a pair of terminals adapted to be connected to a source of alternating current supply, a pair of electronic valves, each of said valves having a cathode and an anode and a controlling grid, circuit means connecting one of said terminals to the anode of one of said valves and to the cathode of the other of said valves, circuit means connecting the other of said terminals to the cathode of said one valve and to the anode of said other valve, translating means in series circuit with one of said circuit means, transformer means having a first winding connected between said terminals and a second winding connected between the cathode and grid of said one valve, a third and a fourth winding for said transformer means, a controlling switch, a circuit connecting said third winding to said terminals through said switch, and a circuit connecting said other terminal through said fourth winding and one of said valves to said one terminal.

5. In an electrical controlling network, a pair of terminals adapted to be connected to a source of alternating current supply, a pair of electronic valves, each of said valves having a cathode and an anode and a controlling grid, circuit means connecting one of said terminals to the anode of one of the valves and to the cathode of the other of said valves, circuit means connecting the other of said terminals to the cathode of said one valve and to the anode of said other valve, translating means in series circuit with one of said circuit means, transformer means having a single core, a first transformer winding connected between said terminals and a second transformer winding connected between the cathode and grid of said one valve, a third and a fourth transformer winding for said transformer means, a controlling switch, a circuit connecting said third winding to said terminals through said switch, and a circuit connecting said other terminal through said fourth winding and one of said valves to said one terminal, said first winding being operable to induce a flux in said core in one direction whereby a bias voltage of one po-

12

larity is applied by said second winding to said one valve, said third and fourth windings being so polarized relative to said first winding that current flow through either thereof will oppose the flux in said core due to current flow through said first winding.

6. In an electrical controlling network, a pair of terminals adapted to be supplied with alternating current energy, a working circuit between 10 said terminals including a pair of back-to-back arranged valve means whereby alternating current flow therethrough may be controlled, each of said valve means having an anode and a controlling grid and a cathode, a transformer having a single core and a plurality of windings about said core, one of said windings being connected between the grid and cathode of one of said valves, a second of said windings being connected between said terminals and arranged to render the potential of the grid of said one valve negative when the potential of its respective cathode is negative with respect to its anode, a switch, a third of said windings being connected through said switch to said terminals and arranged to buck the flux in said core due to said second winding, and a fourth of said windings connected to said terminals through the other of said valves.

7. In an electrical controlling network, a pair of terminals adapted to be supplied with alternating current energy, a working circuit between 30 said terminals including a pair of back-to-back arranged valve means whereby alternating current flow therethrough may be controlled, each of said valve means having an anode and a controlling grid and a cathode, a transformer having a single core and a plurality of windings about said core, one of said windings being connected between the grid and cathode of one of said valves, a second of said windings being connected between said terminals and arranged to render the potential of the grid of said one valve negative when the potential of its respective cathode is negative with respect to its anode, a switch, a third of said windings being connected through said switch to said terminals and arranged to buck the flux in said core due to said second winding, a fourth of said windings connected to said terminals through the other of said valves, and capacitor means connected to said first winding whereby it is operable to discharge therethrough to provide a lagging output voltage for said second winding relative to that between the anode and cathode of said first valve means.

8. In an electrical controlling network, a pair of terminals adapted to be supplied with alternating current energy, a working circuit between 55 said terminals including a pair of back-to-back arranged valve means whereby alternating current flow therethrough may be controlled, each of said valve means having an anode and a controlling grid and a cathode, a transformer having a single core and a plurality of windings about said core, one of said windings being connected between the grid and cathode of one of said valves, a second of said windings being connected between said terminals and arranged to render the potential of the grid of said one valve negative when the potential of its respective cathode is negative with respect to its anode, a switch, a third of said windings being connected through said switch to said terminals and arranged to buck the flux in said core due to said second winding, a fourth of said windings connected to said 70 terminals through the other of said valves, ca-

13

pacitor means connected to said first winding whereby it is operable to discharge therethrough to provide a lagging output voltage for said second winding relative to that between the anode and cathode of said first valve means, and means for limiting the magnitude of current flow through said second and third windings.

9. In an electrical controlling network, a pair of terminals adapted to be supplied with alternating current energy, an inductive working circuit between said terminals including a pair of back-to-back arranged valve means whereby alternating current flow therethrough may be controlled, each of said valve means having an anode and a controlling grid and a cathode, a transformer having a single core and a plurality of windings about said core, one of said windings being connected between the grid and cathode of one of said valves, a second of said windings being connected between said terminals and arranged to render the potential of the grid of said one valve negative when the potential of its respective cathode is negative with respect to its anode, a switch, a third of said windings being connected through said switch to said terminals and arranged to buck the flux in said core due to said second winding, a fourth of said windings, capacitor means connected to said first winding whereby it is operable to discharge therethrough to provide a lagging output voltage for said second winding relative to that between the anode and cathode of said first valve means, resistance means connected across the ends of said fourth winding and having a tap intermediate its ends, circuit means connecting said tap to one of said terminals and one of said fourth winding to the other of said terminals, and capacitor means connected between said tap and the other end of said fourth winding.

10. In an electrical controlling network, a pair of terminals adapted to be supplied with alternating current energy, a working circuit between said terminals including a pair of back-to-back arranged valve means whereby alternating current flow therethrough may be controlled, each of said valve means having an anode and a controlling grid and a cathode, a transformer having a single core and a plurality of windings about said core, one of said windings being connected between the grid and cathode of one of said valves, a second of said windings being connected between said terminals and arranged to render the potential of the grid of said one valve negative when the potential of its respective cathode is negative with respect to its anode, a switch, a third of said windings being connected through said switch to said terminals and arranged to buck the flux in said core due to said second winding, a fourth of said windings connected to said terminals through the other of said valves, capacitor means connected to said first winding whereby it is operable to discharge therethrough to provide a lagging output voltage for said second winding relative to that between the anode and cathode of said first valve means, and capacitor means in series circuit with said second and third windings.

11. In an electrical controlling network, a pair of terminals adapted to be supplied with alternating current energy, a working circuit between said terminals including a pair of back-to-back arranged valve means whereby alternating current flow therethrough may be controlled, each of said valve means having an anode and a controlling grid and a cathode, a transformer having a single core and a plurality of windings about said core, one of said windings being connected between the grid and cathode of one of said valves, a second of said windings being connected between said terminals and arranged to render the potential of the grid of said one valve negative when the potential of its respective cathode is negative with respect to its anode, a switch, a third of said windings being connected through said switch to said terminals and arranged to buck the flux in said core due to said second winding, a fourth of said windings connected to said terminals through the other of said valves, capacitor means connected to said first winding whereby it is operable to discharge therethrough to provide a lagging output voltage for said second winding relative to that between the anode and cathode of said first valve means, and a second means for biasing the grid of said one valve independently of said first winding.

12. In an electrical controlling system, a sequence controlling network, an initiating network for initiating the operation of said sequence network including a pair of back-to-back arranged electronic valves each having a controlling grid and a main electrode, transformer means having a secondary winding and a plurality of primary windings, each said winding having a pair of terminals, means connecting said terminals of said secondary winding between said grid and main electrode of one of said valves, to control the conduction of said one valve, means adapted to connect a source of potential to said terminals of one of said primary windings operable to normally maintain said one primary winding energized whereby said secondary winding is operable to supply a potential to bias the grid of said one valve into a blocked condition, means for selectively connecting the terminals of a second of said primary windings to a source of potential in a direction to oppose the energization of said transformer means by said first primary winding, potential supplying means including the other of said valves connected to the terminals of a third of said primary windings for energizing said third primary winding, in a direction to oppose the energization of said transformer means by said first primary winding, and potential supplying means connected between said grid and said main electrode of said one valve and controlled by said sequence network for biasing said grid and said cathode of said one valve with respect to each other.
